UNITED STATES PATENT OFFICE

2,423,037

ELECTRODYNAMIC LOUD-SPEAKER

John F. Marquis and Carleton T. Weibler, St. Charles, Ill., assignors to Operadio Manufacturing Co., St. Charles, Ill., a corporation of Illinois

Application November 3, 1944, Serial No. 561,776

4 Claims. (Cl. 179—115.5)

1

This invention relates to an acoustic transducer, commonly termed a loud speaker, and employed as an element of a radio receiver or of a public address system.

One object of the invention is to provide a new and improved acoustic transducer, together with an expeditious method of assembling the same.

Another object of the invention is to reduce the overall depth, as compared with that of the conventional acoustic transducer in which the magnetic motor is mounted behind the diaphragm.

It is also an object of the invention to provide a transducer having its magnetic motor assembly disposed in front of the diaphragm without requiring any supporting braces or webs for said motor at the forward side of the diaphragm.

A further object of the invention is the reduction of manufacturing cost by the elimination of the conventional arms and other parts usually required for supporting the magnetic motor in front of the diaphragm.

More specifically, the invention provides a substantial frame or housing disposed behind the diaphragm together with means for rigidly supporting the permanent magnet or electromagnetic motor from the central portion of this housing, the diaphragm being provided with a central aperture through which a supporting connection extends to carry the motor at a position in front of the diaphragm.

Other objects and advantages of the invention will appear from the following description taken in connection with the drawings in which,

Fig. 1 is a substantially axial sectional view of a transducer or loud speaker embodying this invention and provided with a permanent magnet type of motor.

Fig. 2 is a sectional view similar to Fig. 1, but with portions broken away, showing an electromagnetic motor mounted in accordance with the principles of the invention.

Fig. 3 is a front view or elevation of the structure shown in Fig. 1.

Fig. 4 is an axial sectional view showing a step in the assembly process for centering the opening in the diaphragm and positioning the voice coil in accordance with a definite standard.

Fig. 5 is a fragmentary axial section taken substantially at the same plane as Figs. 1 and 2, showing a modified securing means for the magnetic motor.

Fig. 6 is a fragmentary sectional view similar to Fig. 5, showing another modification of the securing means.

2

Fig. 7 is also a fragmentary sectional view similar to Fig. 5, showing a further modification.

While the invention is susceptible of various modifications and alternative constructions, the embodiments shown in the drawing and described hereinafter are by way of illustration only, and it is not intended that the invention be limited thereto or thereby, but that all modifications and alternative constructions falling within the scope of the invention be included herein as defined by the claims.

In Fig. 1, the supporting housing is shown at 1, being of frusto-conical form and terminating in an outer flange 2 to which the periphery of 15 the conical diaphragm 3 is adhesively attached. The central portion of the housing 1 is a flat circular wall 4 reinforced by a disk 5 which may be of somewhat heavier stock than the remainder of the housing 1 to add rigidity to the back wall 20 4, and which is secured thereto by any conventional method such as welding or riveting.

The diaphragm 3 is formed with a central opening surrounded by a short integral collar or flange 3^a, and a centering member 6, in the form 25 of a crimped or corrugated flexible diaphragm, is adhesively secured to this collar 3^a, the peripheral portion 6^a of the centering member being secured to a shoulder 1^a of the housing 1. Said housing 1 may be, and frequently is, made with 30 substantial cut-out areas, giving it the nature of a spider rather than an enclosing housing, and when thus constructed is sometimes termed "basket"; but, if preferred, the conical wall of the part 1 may be continuous, and for the purpose 35 of this invention it is immaterial which design is employed for this part.

In the central opening of the diaphragm 3 there is secured a tubular support 7 which may be of paper or other non-magnetic material having 40 its upper end adhesively fastened to the inner surface of the collar 3^a of the diaphragm and carrying at its lower end the voice coil 8 which acts as the armature of the magnetic motor by which the diaphragm 3 is vibrated. Terminals 45 or lead wires for the coil 8 are not shown in the drawing, but it will be understood that such wires extend from the coil to the radio receiver or telephone system into which the speaker or transducer is connected.

Fig. 1 shows a permanent magnet 10 which is preferably of the alloy type composed of the material known as Alnico V or other suitable magnetic material and a central pole piece 11 extends co-axially from the magnet 10, being secured thereto by a screw 12. The screw also

holds in place the back plate 13 which carries the cylindrical member 14 of the magnetic motor, said member acting as the opposite pole of the magnet and providing an annular air gap 15 in which the voice coil 8 is supported with operating clearance. The magnet 10 and the part 14 are rigidly secured to the reinforced back wall 4, 5 of the housing 1 by means of a clamping bolt or screw 16 extending through the central opening in said back wall and through an annular spacer member 17 of non-magnetic material which is interposed between the back wall and the center pole 11. Preferably, the end of the part 11 is reduced in diameter to fit accurately within a recess in the mating end of the spacer 17, while said spacer is fitted into a central opening in the back wall 4 which does not extend through the reinforcing member 5, but thus provides a centering recess in which the spacer 17 may be fitted and clamped by means of the screw 16. Preferably, the screw is provided with a locking washer 18 disposed between its head and the part 5.

The structure shown in Fig. 2 is substantially identical with that shown in Fig. 1 except that instead of the permanent magnet 10, the motor includes an electromagnet having an inductor coil 20, and the central pole 21 extends throughout the depth of this coil and is shown with a reduced portion 22 which is riveted over the end plate 13 by which the outer pole 14 is carried. The remaining parts being similar to those shown in Fig. 1, they are designated by corresponding reference numerals.

As indicated in Figs. 1 and 3, the flange 2 of the supporting housing terminates in an annular flange portion 2^a which serves to center and confine the edge of the diaphragm 3 and a mounting gasket or cushion ring 23 which is adhesively fastened to this marginal part of the diaphragm in position to contact the face of a baffle or panel on which the speaker may be mounted by bolts or screws passing through the parts 2, 3 and 23. In previous devices of this character in which the magnetic motor was mounted in front of the diaphragm adjacent its concave side, the motor was supported by radially extending arms or webs attached to the outer flange 2 of the housing and usually to secure a smooth and finished appearance it was necessary to notch or interrupt the gasket 23 to accommodate the ends of these arms. With the present structure, such supporting arms are eliminated and the additional work on the gasket 23, together with the labor of securing the supporting arms in position, is avoided.

To simplify the assembly and to insure not only that the magnetic motor will be properly centered and fitted within the voice coil, but also that it will be interchangeable with a replacement motor, if required, the special jig, shown in Fig. 4, may be employed in fitting the diaphragm and voice coil into the housing. The voice coil 8 and its supporting cylinder 7 are fitted onto a plug 30 and the diaphragm and centering member 6 are then glued to the part 7 in their correct relative positions. The plug 30 includes a reduced portion 31 which fits into the central recess of the back wall 4, while a reduced threaded portion 32 extends through the central opening in the part 5 so that a wing nut 33 may be applied to clamp the plug 30 in position during the period required for drying the glue which holds the parts 3, 6 and 7 together. As soon as the plug 30 has been

inserted in the back wall the peripheral portion 6^a of the centering member 6 may be glued in position on the shoulder 1^a and the outer edge of the diaphragm 3 may be adhesively secured, if desired, in the cupped flange 2 of the housing, and may be clamped therein with the gasket 23 in position. At the end of the drying period the plug 30 is removed, thus leaving the central opening in the diaphragm 3 accurately positioned with respect to the central openings in the back wall 4, 5 so that when a magnetic motor is installed it will be properly centered with respect to the diaphragm and the voice coil 8.

Fig. 5 shows a modified construction in which a spacer 40 is substituted for the spacer 17 and is formed with a conically tapered portion 41 fitting into a conical recess 42 in the plate 5^x attached to the back wall 4. The bolt 43 thus draws the spacer 40 and the attached center pole 21 (or 11) snugly into position, the end of the tapered portion 41 being made slightly underflush with respect to the outer surface of the plate 5^x to insure that it will be drawn tightly into the conical socket 42 by the screw 43. Preferably, a relatively large clamp washer 44 is disposed under the head of the screw 43 to distribute the clamping pressure, and the lock washer 45 is included to hold the parts in adjusted position.

In the arrangement shown in Fig. 6 the non-magnetic spacer 50 is fitted to the end of the center pole 21 (or 11) in the same manner as heretofore described, but the outer end of the spacer is threaded at 51 to engage corresponding threads 35 in the plate 5^y secured to the back wall 4. A lock nut 52 is then screwed onto the protruding threads 51 of the spacer. The screw 53 acts independently of these parts to perform the single function of securing the spacer 50 to the center pole 21, and a lock washer 54 is provided to prevent loosening of this connection in operation.

Fig. 7 shows a further modification in which the non-magnetic spacer 60 on the pole 21 (or 11) includes a reduced portion 61 which fits snugly in a central opening in the plate 5^c secured to the back 4. This reduced portion 61 is slightly underflush with respect to the outer face of the plate 5^c to insure being drawn snugly into position by the clamp screw 62 which operates against a clamping washer 63 and is provided with a lock washer 64 directly under its head.

It will be seen that with any of the structures herein described, or with modifications involving the same principles, the magnetic motor will be firmly and rigidly supported at the front side of the diaphragm so as to occupy space within the cavity of the diaphragm, thus providing a very compact structure as compared with transducers in which the motor is mounted behind the diaphragm; but that this arrangement does not require the use of supporting arms extending radially from the magnetic motor to the rim of the housing and thus projecting in front of the diaphragm and more or less impairing the propagation of sound therefrom. It will also be evident that with the standardized positioning of the central opening in the diaphragm and in the voice coil which is rendered possible by use of the assembly plug herein described, any properly constructed motor may be fitted accurately into place so as to function efficiently with this assembly, and if repair or replacement of the motor should become necessary it can be readily removed and remounted or replaced with equal accuracy and with a minimum of time and skill.

It will be understood that if the supporting housing is made of magnetic material, such as steel, the spacer 17, (or 40, 50 or 60) will be preferably formed of non-magnetic material, such as brass or aluminum, and in that case the screw 17 (or 43, 53 or 62) should also be of non-magnetic material. If the housing itself is non-magnetic, the other parts may be made of steel, although it will still be preferable to have them of non-magnetic metal so that the polar flux will tend to be concentrated in the vicinity of the voice coil.

We claim as our invention:

1. A loud speaker comprising a rigid unitary supporting housing having the general outline of the frustum of a cone, said housing having a wall at the small end and having accurately finished supporting means at said wall, a sub-assembly comprising a voice coil support, speaker diaphragm and cylindrical voice coil, said speaker diaphragm being of the conical type with the small end joined to said voice coil, means for securing the large end of said speaker diaphragm to the large end of said housing, means for securing said voice coil support to the housing in an accurate position with respect to the finished supporting means of said housing wall to accurately pre-position said voice coil, a two-piece field structure comprising an axial pole piece and annular pole piece, said two pole pieces having accurately finished surfaces defining an annular air gap adjacent one end of said axial pole piece, means for rigidly supporting said annular pole piece solely from said axial pole piece at the other end of said axial pole piece, said axial pole piece having the one end thereof accurately finished to cooperate with the finished supporting means at said housing wall and means for rigidly supporting said axial pole piece at said one end only from said housing wall, said field structure being adapted to be symmetrically disposed with-

in the space enclosed by said housing with the accurately finished housing part and axial pole end cooperating to provide an inverted dynamic speaker assembled in preadjusted centered relation.

5 2. The structure of claim 1 wherein said means
for maintaining said field structure against said
housing comprises readily removable locking
means accessible from the outside of the small
10 end of the housing.

3. The structure of claim 1 wherein said housing is shaped to provide an annular flange adjacent to and symmetrical with said wall and wherein said voice coil support is secured to said flange.

4. The structure of claim 1 wherein said housing is shaped to provide an annular flange adjacent to and symmetrical with said wall and wherein said voice coil support is a solid annular member having the outer end secured to said flange with said housing forming an enclosed air chamber between said voice coil support and housing end wall.
